UNITED STATES PATENT OFFICE.

GUSTAV TEIKE, OF TANGERHÜTTE, GERMANY.

TOOTHED-WHEEL-MOLDING MACHINE.

No. 900,327.

Specification of Letters Patent.

Patented Oct. 6, 1908.

Application filed December 26, 1907. Serial No. 408,208.

To all whom it may concern:

Be it known that I, GUSTAV TEIKE, a subject of the King of Prussia, German Emperor, residing at Ironwork, Tangerhütte, 5 Germany, have invented a new and useful Improvement in and Relating to Toothed-Wheel-Molding Machines, of which the following is a specification.

The present invention relates to a molding 10 machine for toothed wheels in which the model teeth mounted on a movable arm are step by step advanced by a forwarding mechanism. Heretofore these machines permit only a difficult or incorrect adjusting of 15 the advance of the teeth or necessitate for each division a special exchangeable mechanism respectively allow only a limited number of divisions.

The molding machine according to my invention is at once adjustable with the greatest exactness for any division or any number 20 of teeth without exchanging any part or without fearing inaccuracies during the forwarding motion. This effect is attained by 25 moving the well known radially adjustable model-tooth support by an adjusting mechanism consisting of mutually adjustable, step like movable and progressing parts which mechanism relates in its micrometer division 30 to the circumference of an exactly fixed circle.

In the accompanying drawing in which I have illustrated my invention like letters of 35 reference refer to like parts throughout the different views.

In said drawings: Figure 1 illustrates a plan view of the whole machine. Fig. 2 shows a longitudinal section of the frame. Fig. 3 shows a plan view of the advancing mechanism ready for work. Fig. 4 shows the same 40 view as Fig. 3 but with advanced stop. Fig. 5 shows the same as Fig. 3 in the moment of the completed micrometer adjustment. Fig. 6 shows a front view of the machine. Fig. 7 shows the end view of the left part of 45 the machine. Fig. 8 shows the center view of the right part of the machine.

The wheel is first designed in a well known manner, like any ordinary belt wheel and 50 the cutting out pattern removed. In its place the guide ring *b* is fixed on the spindle *a*. The ring consists of an exactly turned rim of a fixed diameter providing a groove *c* in which divisions for the different numbers 55 of teeth are arranged figured for the outer circle of the rim. Above the box of the

ring a guide piece *d* rotates on the spindle *a* in a well known manner. This guide is provided for radially respectively diametrically movable arms *e* provided with divisions for 60 their longitudinal adjustment. A gearing *f* enables its easy and exact adjustment. The model teeth *g* are located at one or at both ends of these arms. The teeth can be moved downward in any of the well known manners. In the drawing they are illustrated as being fixed.

The exact regulation of the progressing rotation of the arms *e* around the spindle *a* is effected by means of the mechanism illustrated in Figs. 3—8, the motion of which is transmitted by an arm *h* of a lever the other end of which slides in a flat and exactly constructed guide *i* of the guide piece *d* where it can be adjusted by a set screw *k*. This 70 mechanism permits a vertical motion of the guide piece *d* and the arms *e* together with the model teeth whereby a special moving mechanism for the teeth is made unnecessary *e. g.* in smaller molding machine. 80

The advancing mechanism of the machine consists of a clamp *l* moving and temporarily adjustable on-the ring *b*. The clamp *l* provides a tongue *m* bent corresponding to the outer circumference of the guide ring *b* and carrying on its front a division in millimeters *n*. A hollow slide *o* also movable and adjustable on the guide ring *b* can be slid over said tongue and provided in a section the nonius. The slide *a* further provides a projection *p* against which a finely divided micrometer screw *q* movably and adjustably mounted on the clamp *l* pushes. The projection *p* can be caught from the rear by a hook *r* movably and adjustably 90 mounted on the clamp *l*. 95

In order to facilitate and simplify the working of said mechanism I place the division in a cutting *c* of the guide ring *b*.

The operation of the machine is as described hereafter. The clamp *l* is fixed on the ring *b* and the guide shell *o* according to the division forwarded to the millimeter division *n* with the help of the nonius. The slide carrying the micrometer is then adjusted towards the projection *p* and fixed whereafter the micrometer screw is correspondingly adjusted whereby the guide *o* is moved fractions of millimeters (Fig. 5). The hook *r* is now placed against the projection *p* and screwed fast. After the micrometer slide is redrawn the play of the hollow 100 105 110

guide *o* (Figs. 3, 4) between the clamp *l* and the hook *r* now corresponds to the division exactly fixed even by fractions of millimeters. I now move the mechanism, *l*, *o*, 5 towards the lever arm *h* fixed on the guide ring *b*, fix the clamp *l*, mold by a downward pressure or the like the model teeth in the molding wall, lift the same, release the set screw of the lever arm *h* and remove the 10 guide *o* from the clamp *l* until it pushes against the hook *r* whereby the lever *h* and with it the model teeth is also forward the exact part of the division. The lever *h* is fixed, the clamp *l* moved towards the guide *o* 15 by releasing its set screw from the ring *b*, and fixed again. After the second tooth is now molded the process is repeated until all teeth are molded.

What I claim as new and desire to secure 20 by a United States Letters Patent is:—

1. In a tooth wheel molding machine, the combination of a fixed ring (*b*), an exactly adjustable clamp (*l*), an exactly adjustable sliding shell (*o*), means to guide clamp and 25 shell in a circle on the fixed ring, a stop (*p*) located on the shell, and an adjustable hook (*r*) mounted on the clamp and catching behind the said stop, substantially as described and for the purpose set forth.
2. In a tooth wheel molding machine, the combination of a fixed ring (*b*), an exactly adjustable clamp (*l*), an exactly adjustable sliding shell (*o*), a lever (*h*), a box (*d*), a slotted guide (*i*) fixed to said box, means to 30

adjustably connect the one end of said lever 35 in said guide, means to fix the other end of said lever to the fixed ring, a carrier (*e*) for the model tooth and means to lower or lift the box (*d*) with the carrier (*e*) and the model tooth (*g*) substantially as described 40 and for the purpose set forth.

3. In a tooth wheel molding machine, the combination of a fixed ring (*b*), an exactly adjustable clamp (*l*), an exactly adjustable sliding shell (*o*), means to guide clamp and 45 shell in a circle on the fixed ring, a stop (*p*) located on the shell, an adjustable hook (*r*) mounted on the clamp and catching behind the said stop, and a micrometer screw (*q*) adjustable and movably mounted on the 50 clamp (*l*) substantially as described and for the purpose set forth.

4. In a tooth wheel molding machine, the combination of an arm (*h*), a fixed ring (*b*) of fixed diameter, a groove (*c*) on said fixed ring, a division located in said groove, an exactly adjustable clamp (*l*), an exactly adjustable sliding shell (*o*), and means to move clamp and shell towards or from each other, substantially as described and for the 55 purpose set forth.

In testimony whereof, I have signed my name to this specification, in the presence of two subscribing witnesses.

GUSTAV TEIKE.
